UNITED STATES PATENT OFFICE.

EDWARD HETT, OF NEW YORK, N. Y.

ART OF MAKING PRINTING-SURFACES.

SPECIFICATION forming part of Letters Patent No. 637,595, dated November 21, 1899.

Application filed October 4, 1899. Serial No. 732,439. (No model.)

To all whom it may concern:

Be it known that I, EDWARD HETT, a citizen of the United States, and a resident of New York, (New Dorp,) in the county of Richmond 5 and State of New York, have invented certain new and useful Improvements in the Art of Making Printing-Surfaces, of which the following is a specification.

This invention relates to a new and useful 10 improvement in the art of making printing-surfaces suitable for planographic, relief, intaglio, or other printing.

In that branch of the art to which my invention is most nearly related it has heretofore been the practice in making printing-surfaces to first make a basic surface by sticking up by hand and with great care a number 15 of transfers upon a flat support called a "setting-up plate." These transfers are usually 20 thin pieces of paper bearing copies in black ink of the design or matter to be printed by a printing-surface. The designs on the transfer-paper are generally printed thereon and without any special reference to the absolute 25 or relative location of the designs on the various transfer-papers. Where several printing-surfaces are to coöperate in printing, as in multicolor-work, it is essential that the transfers for each printing-surface be very 30 carefully stuck up on the setting-up plate in accordance with certain matching guiding- 35 marks previously located on each transfer when the transfer is made and on the setting-up plate with reference to the register of the printing-surfaces which when completed are 40 to coöperate in printing. When a basic surface has been thus prepared, it has been the practice to lay it upon the surface, generally a flat stone, which is to become the printing- 45 surface. Scrapers are then passed over the setting-up plate, so as to exert proper pressure, and, the setting-up plate being removed, the transfers are found turned over from the setting-up plate upon the stone. The trans- 50 fer-paper is then soaked off, but the ink of the transfer remains on the printing-surface, and the surface is then developed, as by etching, and thus becomes a printing-surface. In cases where it is necessary to employ a plu- 55 rality of printing-surfaces in printing a job it has been the practice, according to this old process, to make each of the printing-surfaces

in the same way, starting always with the setting-up plate and the transfers turned over therefrom upon each surface to be made into 55 a printing-surface. Whatever may be the number of printing-surfaces required for a job, it was necessary to form each in the same way from its particular basic surface previously prepared and with the same painstaking care, especially in regard to accuracy of register. Again, where in some cases it was desired to duplicate the printing-surfaces, so that those worn out might be replaced or so that the printing might proceed on different 60 presses at the same time with duplicate printing-surfaces, it was necessary to form these 65 duplicate printing-surfaces each in the same way and always from a new and original basic surface previously prepared and each with 70 the same expenditure of care, time, and labor. Thus the making of the printing-surfaces added greatly to the final cost of the job, and this 75 cost increased in proportion to the number of printing-surfaces required.

The invention consists in its generic aspect in the process of making a printing-surface, whether planographic, relief, intaglio, or otherwise, from a previously-prepared printing-surface, which for convenience may 80 be here called a "primary printing-surface" or a "primary surface," by printing from said primary surface—that is, taking an impression in any suitable manner from said 85 surface—directly or indirectly upon or to a 90 surface adapted to be developed into a printing-surface, said bodies or couple being arranged in a definite and predetermined co-operating relation both longitudinally and transversely with reference to pre-established 95 guides, for the purpose hereinafter explained. The surface which thus receives the design from the primary surface I herein for convenience term the "secondary surface," and when developed the "secondary printing-surface." By the use of the pre-established 100 guides or guiding means, which may vary widely in character and arrangement, the design of the primary surface may be located on a secondary surface in an exact predetermined position both longitudinally and transversely and also with reference to register, and from a series of registering primary surfaces a series or a plurality of series of regis-

tering secondary printing-surfaces may be made. The secondary surfaces are made of a permanent size and shape to adapt them to fit in a preestablished seat in a printing-press, 5 so that they may be mounted at once in place in the press and without any special adjustment for register be made to print in accurate register.

It also consists in various steps and combinations of steps conducive to the desired result and of more or less particular advantage, as will hereinafter appear and be set out in the claims.

In carrying out the process I may begin 15 with a primary surface made by any suitable process or may and generally do begin, as a preliminary to the present process, by first making the primary surface, preparing for this purpose a basic surface, preferably by 20 sticking up ordinary transfers bearing the design to be printed upon a setting-up plate and turning over these transfers in the usual way upon a printing-surface, which is then suitably developed and becomes the so-called 25 "primary surface." This primary surface may be of stone, zinc, aluminium, or other suitable material and may be developed so as to be a planographic, relief, intaglio, or other printing surface. The primary surface 30 is generally graduated—that is, the design thereon is so made as to be capable of printing an impression in which the ink will be distributed on the impression-surface in graduated quantities for light and shade effects, 35 depth of color, &c. The primary surface and secondary surface are then arranged in a definite and predetermined coöperating relation, so that the former works as required with reference to the latter and with reference to the 40 position which it is desired the design of the primary surface shall occupy on the secondary surface when imparted thereto. For this purpose the primary surface and the secondary surface are arranged in preestablished 45 seats on suitable supports prepared for them in a machine in which the process of imparting the design of the primary surface to the secondary surface is most conveniently carried out, the preestablished guides being employed 50 for quickly and with absolute accuracy arranging the primary and secondary surfaces in their proper coöperating relation. The inked design of the primary surface is then carried over from the primary surface and imparted to or upon the secondary surface directly or indirectly, but without the intermediate employment of a setting-up plate. The secondary surface is then developed, so as to 55 become a printing-surface, and is then the so-called "secondary printing-surface." Like the primary surface it may be of stone, zinc, aluminium, or other suitable material and may be developed so as to be a planographic, relief, intaglio, or other printing surface, and 60 the development of the secondary surface may or may not be in accordance with the method employed in developing the primary

surface. For example, the primary surface may be a relief or intaglio surface and the secondary surface may be so developed as to 70 be a planographic surface, or vice versa. Neither the character or material of one of these surfaces, whatever it may be, has any necessary dependence upon the character or material of the other. In making the primary and secondary printing-surfaces either or both may be developed by light or deep etching or by any other suitable method and may be routed out.

There are various ways in which the design 80 of the primary surface may be printed upon or imparted to the secondary surface by the primary surface, all of which are within the scope of my invention. The design of the primary surface may be printed directly upon 85 a conveying-surface, which is then brought into contact with the secondary surface, so as to impart thereto the design which it has previously taken from the primary surface, the conveying-surface being an intermediate 90 between the primary surface and the secondary surface and being a basic surface for the secondary surface, or the primary surface may be made to print directly upon the secondary surface, in which case the latter surface when developed would print the same 95 design as the primary surface, but in reverse. In cases where an intermediate conveying-surface is employed it may, as preferred, be 100 in the form of a fabric, as transfer-paper, stretched over a suitable support and be brought into firm contact with the secondary surface and turned over thereupon, or the conveying-surface may be a sheet of paper, rubber, or other suitable material and held 105 on a support from which the conveying-surface is not separated when such surface is brought into contact with the secondary surface, but which remains firmly secured on its support during this operation. When the conveying-surface is of paper and whether it is 110 held on its support during the operation of imparting the design to the secondary surface or is turned over from its support upon the secondary surface, new or successive conveying-surface must take the place on the support of the one used and preferably the identical place in imparting the design to new or successive secondary surfaces. When the conveying-surface is of rubber or some other 115 material admitting of repeated use, it is permanently held on its support, the ink residuum, if any, being washed off or otherwise removed before beginning its work for each new and different design to be imparted to a 120 secondary surface.

I preferably employ a conveying-surface in carrying over and imparting the design to the secondary surface, the conveying-surface generally being of transfer-paper, and after receiving the design from the primary surface being turned over upon the secondary surface. The secondary surfaces are preferably identical and interchangeable, especially where 130

they are to carry the same design, and where they are to carry different designs intended to coöperate in printing, as in multicolor-printing, they are designed and constructed 5 for register when completed as printing-surfaces. In using the conveying-surface in practice it is mounted in a machine with the primary surface and the secondary surface, the primary surface and secondary surface 10 being arranged in a definite and predetermined coöperating relation both longitudinally and transversely, and preferably in the same or equivalent definite and predetermined coöperating relation both longitudinally and transversely with respect to the conveying-surface and with reference to pre-established guides. For this purpose I mount the conveying-surface and the coacting primary and secondary surfaces in the machine 15 each in its own separate assigned place or pre-established seat. The secondary surface is made removable, so that successive secondary surfaces may be arranged in the same place, and thus be arranged in the same relation with respect to the conveying-surface or successive conveying-surfaces and receive 20 identical designs from the same primary surface, and when the secondary surfaces are identical the identical designs imparted there- 25 30 to will be identically placed, so that these secondary surfaces may be interchangeable in the subsequent printing. The same result may be attained, however, by imparting a design to a secondary surface mounted in the machine in the particular place assigned for it and then mounting the next secondary surface in the same place occupied by the primary surface, the primary surface having been previously removed after having printed 35 40 its design on the conveying-surface. In this case the two successive secondary surfaces are arranged not in the same but in equivalent definite and predetermined coöperating relation with respect to the successive conveying-surfaces. In making a series of registering secondary printing-surfaces designed 45 to coöperate in printing each secondary surface, being constructed and designed for register, and its corresponding primary surface 50 55 are arranged in the same or equivalent definite and predetermined coöperating relation with respect to their conveying-surface. Moreover, in making a plurality of secondary surfaces from the same primary surface, whether through the intermediation of a conveying-surface or successive conveying-surfaces or not, the successive secondary surfaces are arranged in the same or equivalent coöperating relation with respect to the primary surface. After the secondary surface 60 65 has received its imprint of the design from the primary surface and has been developed in suitable manner it may then be inked, mounted in a press, and used as a printing-surface. Thus it will be seen that the printing-surface—viz., the secondary printing-surface—is made or derived from a previously-prepared

printing-surface—viz., the primary surface—and without the intermediate employment of a setting-up plate, which after the primary 70 surface has been made has no further utility. It will also be seen that two or more secondary printing-surfaces may be derived also from the primary surface, and two or more secondary printing-surfaces, or one or more 75 such surfaces with a primary surface, constitute a plurality of printing-surfaces adapted to be used in printing the same design. This plurality of printing-surfaces for the same design is very useful in cases where it is desired to run two or more presses upon the same job or when one or more extra printing-surfaces are required to take the place of a printing surface or surfaces which have been worn out or become impaired by use in printing or otherwise. This plurality of printing-surfaces capable of indefinite multiplication or increase makes it possible, moreover, to print from such surfaces the same design indefinitely and beyond the limit of wear of an 80 85 individual printing-surface. Again, from a series of registering primary surfaces a series or a plurality of series of secondary printing-surfaces adapted to coöperate in printing may be readily made, the designs being imparted 90 95 from the series of primary surfaces to each series of secondary surfaces in accurate and predetermined position and with reference to register as printing-surfaces, and each secondary surface of a series may be made identical and interchangeable with the corresponding members of the other series. Moreover, much time, labor, and painstaking care are saved by the new process in preparing a plurality of printing-surfaces as compared with 100 105 the old process of preparing each printing-surface directly from a manually-prepared basic surface. In the practical use of the invention a plurality of designs is imposed upon the primary 110 printing-surface in accurate predetermined mutual relation with reference to the printing of those designs by the secondary printing-surface in accurate predetermined positions on the impression-surface and with reference to 115 register. This plurality of designs is generally imposed upon the primary surface by sticking up a plurality of ordinary transfers upon a setting-up plate in accurate predetermined mutual relation which they are to have upon 120 125 the secondary surface. These transfers are then turned over upon the primary surface, which is thereupon developed, so as to be capable of printing. The secondary surface has imparted to it from the primary surface this plurality of designs in the same identical mutual relation. To accomplish this result, I may bring the primary printing-surface and the secondary surface into direct contact, or, as is preferred, I may impart the designs of 130 135 the primary surface to a conveying-surface, from which the designs are then imparted to the secondary surface. Thus it will be seen the secondary surface has imparted to it a

plurality of designs in accurate predetermined mutual relation and from a unitary surface bearing said designs in the same identical relation, the primary surface or the conveying-surface being a unitary basic surface with respect to the secondary surface.

The general procedure and the various details followed in practically carrying out the steps of the process will hereinafter more particularly appear in connection with the description of the mechanism shown in the accompanying drawings.

In the drawings forming part of this specification I have illustrated a complete machine capable of economically and readily carrying out the various steps of the process above described. I have also illustrated several modifications of mechanism diagrammatically for the purpose of indicating generally that the invention is not confined to any particular and specific form of machine or mechanism.

Referring now more particularly to the various views, in which like figures designate corresponding parts, Figure 1 is a side elevation of the machine referred to and looking in the direction of the arrow 1, Fig. 4. Fig. 2 is a side elevation looking in the direction of the arrow 2, Fig. 4. Fig. 3 is a vertical sectional elevation on the line 3, Fig. 4. Fig. 4 is an end elevation. Fig. 5 is a central broken plan view. Fig. 6 is a sectional elevation on line 6 6 of Fig. 1. Figs. 7 and 8 are respectively a side and fragmental front elevation of the inking-frame and inking-rollers. Figs. 9 and 10 are respectively a side and fragmental front elevation of the damping-frame and damping-rollers. Figs. 11 and 12 are respectively an outer side elevation and plan view of certain mechanism for shifting the supporting-cylinder for the conveying-surface. Fig. 13 is a sectional elevation on the line 13 13, Fig. 11. Fig. 14 is a broken plan view of the supporting-cylinder for the conveying-surface. Fig. 15 is a broken vertical section of the same on the line 15 15, Fig. 16. Fig. 16 is an end elevation of said cylinder looking in the direction of the arrow 16, Fig. 14. Fig. 17 is a sectional elevation on the line 17, Fig. 15. Figs. 18, 19, and 20 are end views of said cylinder, showing various positions of the paper-carrier in stretching the paper over the supporting-cylinder. Figs. 21, 22, 23, and 24 are diagrammatic end views of the said cylinder and the secondary surface and showing their relation in the operation of turning over a transfer from the former upon the latter. Fig. 25 is a diagrammatic view of a modification and showing a primary surface and a secondary surface coöperating together in the same machine, so that the former prints directly upon the latter. Fig. 26 is a diagrammatic view of a modification and showing primary and secondary surfaces and a conveying-surface coöperating together in the same machine, the conveying-surface being in the form of a permanent substance—rubber, for example—which carries over the design from

the primary surface to the secondary surface. Fig. 27 is a diagrammatic view of a modification and showing primary and secondary surfaces and a conveying-medium coöperating together in the same machine, the conveying-surface being in the form of a temporary fabric—paper, for example—which remains on its support while carrying over the design from the primary surface to the secondary surface and is then torn off. Figs. 28 and 29 are respectively a broken plan and a longitudinal section of a secondary printing-surface mounted on its support.

Of the various types of machines with which my process in its broadest aspect may be carried out I prefer to employ the complete organized machine shown in Figs. 1 to 20, inclusive. In this type there are primary and secondary surfaces and a conveying-surface. The machine is organized with special reference to securing the desired manipulation and coöperation of these three elements—that is to say, there is mechanism for bringing the primary surface and conveying-surface into coöperating contact and mechanism for bringing the conveying-surface and secondary surface into coöperating contact, such mechanism being preferably arranged with a view to securing the required register when the secondary surface comes to be used as a printing-surface. Inasmuch as a primary surface and a secondary surface, with or without a conveying-surface, have never heretofore, so far as I am aware, been associated in a definite and predetermined coöperating relationship both longitudinally and transversely with reference to preëstablished guides, so as to coöperate for the purpose of making a secondary printing-surface and locating the design thereon in a definite predetermined position and with reference to register, it will be seen that the process may be carried out by various types of machines or apparatus.

In practicing the process in its most advantageous form the secondary surfaces are cylindrical and preferably are shell-like and tubular and made removable from rotary supports, so that after the secondary surfaces have been made into secondary printing-surfaces they may be seated on appropriate supports and in the required accurate positions in a printing-press. The primary printing-surface may be and for convenience preferably is constructed in the same manner. When the primary and secondary surfaces are thus made removable and replaceable on their supports, it will be seen that guiding means or preëstablished guides will be necessary to insure that they are made to occupy their preëstablished seats on their supports. This the invention provides for.

I will now describe the process in its various details by specifically describing the particular machine shown in the drawings, omitting generally from such description for the sake of clearness further statements designed

to indicate what are and what are not the essentials of the invention in its more or less generic aspect.

1 is the primary surface, cylindrical in form and preferably shell-like and continuous and removable from its supporting-cylinder 2, which is secured on the shaft 3, turning in boxes 4. This primary surface is suitably developed and when inked is ready to print the design which it is desired to carry over and impart to the cylindrical secondary surface 5 on the support 6, secured on the shaft 7, which turns in the boxes 8. The secondary surface 5 is also preferably continuous and removable from its support.

In Figs. 28 and 29 is shown the preferred arrangement for the secondary surface. The secondary surface is there shown as a continuous cylindrical shell-like tube with a seamless exterior. The secondary surface has a cylindrical support 6, the former having a slight interior taper and the latter a corresponding exterior taper, so that the secondary surface may be easily removed from its support, which contacts with and firmly supports every point of the internal periphery of the secondary surface. In order that the secondary surface 5 may be readily mounted always exactly in its predetermined seat on its support 6, suitable guiding means for this purpose are provided, which insure absolute identity and accuracy of position at all times both longitudinally and circumferentially. The guiding means for circumferential location shown in the drawings consists of two opposite longitudinal grooves 220 and 221, accurately cut on the exterior surface of the supporting-cylinder 6, and corresponding ribs 222 and 223, formed on the interior of the secondary surface and adapted to slide and accurately fit in these grooves, a marked rib of the secondary surface in a marked groove of the support. For the purpose of insuring identity and accuracy in the longitudinal position of the secondary surface on its support the support is provided with a collar 224, screwed on one end of the support to form a fixed abutment, against which one end of the secondary surface accurately fits when in place on its support. The secondary form is locked in place against any accidental longitudinal movement by the clamps 225 and screws 226 on the opposite end of the support. The support 6 is generally provided at one end, on which the collar 8 is fixed, with a screw 227, extending through a nut 228, adapted to travel to and fro on the screw in the slot 229 in the support 6 and arranged to start the secondary surface from its seat by the rotation of the screw. If desired, the support 6 may be so constructed as to be removable from its shaft 7, the support being seated on the shaft against the collar 230 by keys 231 entering slots 232 in the shaft, and, if required, the secondary surface may be fixed permanently on its support, the collar 230 and the keys 231 serving

as guiding means whereby the removable support may be accurately located both longitudinally and transversely in a predetermined position on the shaft. It is preferred, however, to make the secondary surface removable from the support 6. The primary surface is preferably arranged and constructed in the same way.

9 is a shaft turning in boxes 10 and carrying the drum or support 11 for the conveying-surface 12, adapted to receive an imprint from the primary surface 1 and carry it over or impart it to the secondary surface 5.

The inking-frame 13, carrying the inking-rollers for the primary surface 1, is fixed on the shaft 15, so as to be swung thereby to and from the primary surface. On the opposite side of the machine and fixed on the shaft 16 is the inking-frame 17, carrying the inking-rollers for the secondary surface 5. The frames 14 and 18 for the damping-rollers for the respective printing-surfaces are loosely mounted on the shafts 15 and 16, respectively, so as to turn thereon when moved to and from their printing-surfaces, as will hereinafter more fully appear. The inking and damping frames and rollers for the primary and secondary surfaces 1 and 5 are similar and similarly mounted and actuated. Their details will be described later on.

The main driving-shaft 19 of the machine is actuated from any suitable source of power, as the electric motor 20, and carries the fixed gear 21, which meshes with the gear 22, fixed on the shaft 23, which may be called the "power-distributing" shaft, because the power for driving the primary and secondary and conveying surfaces and inking and damping rollers is derived from this shaft 23. For the purpose of this distribution of power the shaft 23 is provided with suitable clutches 24 and 25. The clutches 24 and 25 are operated, respectively, by the clutch-shafts 27 and 28, provided with hand-levers 29 and 30. The clutches 24 and 25 make fixed and loose the gears 31 and 32, respectively, on the shaft 23. The shaft 23 is carried in brackets 26, fixed on the main frame. (See Fig. 2.) The gears 31 and 32 mesh, respectively, with the gears 33 and 34, fixed on the short shafts 35 and 36, supported by the main frame and the brackets 37 and 38, respectively. The shaft 36 has fixed thereon gears 39 and 40, the former meshing with gear 41, which is loose on the shaft 16, and meshes with idle gear 42, meshing with gear 43, fixed on the shaft 7, which carries the secondary surface 5. The gear 40 meshes with gear 44, secured to the main ink-distributing cylinder 45, which is sleeved to rotate on the shaft 16. The short shaft 35 on the opposite side of the machine from shaft 36 has fixed thereon the gears 46 and 47. The gear 46 meshes with the gear 48, which is loose on the shaft 15, and meshes with the idle gear 49, which meshes with the gear 50, fixed on the shaft 3, which carries the primary surface 1. The gear 47 meshes

with the gear 51, which is secured to the main inking-cylinder 52, sleeved to rotate on the shaft 15. It will thus be seen that by operating the clutch 25 to lock the gear 32 on the shaft 23 the secondary surface is driven through the train of gears 32, 34, 39, 41, 42, and 43 and that the inking-cylinder 45 is likewise driven through the train of gears 32, 34, 40, and 44. It will likewise be seen that by operating the clutch 24 to lock the gear 29 on the shaft 23 the primary surface is driven through the train of gearing 31, 33, 46, 48, 49, and 50 and that the inking-cylinder 52 is driven through the train of gears 31, 33, 47, and 51. The inking-roller 53 carries a gear 54, which meshes with the gear 44 and with a gear on the reciprocating inking-roller 55, which supplies the form-inking rollers 56 and 57. An idle gear 58 on the frame 18 meshes with the gear 44 and with a gear on the damping-roller 59, which supplies the form-damping rollers 60 and 61. Thus it will appear that these inking and damping rollers are driven with the secondary surface 5 to supply that surface with ink and water as may be required in developing said surface into a printing-surface. On the opposite side of the machine the inking and dampening rollers are similarly arranged and geared. The ink-distributing roller 62 carries a gear 63, which meshes with the gear 51 and with a gear on the reciprocating inking-roller 64, which supplies the rollers 65 and 66. An idle gear 67 on the frame 14 meshes with the gear 51 and with a gear on the water-roller 68, which supplies water to the rollers 69 and 70. The inking and dampening rollers for the primary surface are for the purpose of supplying that surface with ink and water, so that it may print the design thereof as required. When the inking and dampening rollers are not required, they are swung back from their printing-surfaces, but these surfaces may still be driven by the idle gears 42 and 49. The inking-frames 13 and 17 are swung back by the worm-shafts 71 and 72, respectively, having the hand-wheels 73 and 74. These worm-shafts actuate the worm-wheels 75 and 76, fixed on the shafts 15 and 16, on which the inking-frames are respectively fixed. The dampening-frames 14 and 18, carrying their water-rollers, are swung back from their printing-surfaces when not required by the crank-shafts 77 and 78, carrying, respectively, the cranks 79 and 80, connected with their frames by links 81 and 82. The crank-shafts are driven by the gears 83 and 84, fixed thereon and actuated, respectively, by gears 85 and 86, operated by the hand-wheels 87 and 88. The boxes 4 for the shaft 3 are adjusted vertically in their recesses in the main frame by the lower screws 89 and the upper screws 90, the latter working through arms 91, pivoted on the main frame, so that they may be swung aside when the boxes are to be lifted from place. For the purpose of lateral adjustment I provide eccentrics 92 in the boxes 4, in which the shaft

3 rotates. By turning the eccentrics the shaft, with its printing-surface, is moved laterally. Vertical adjustment may also be obtained by these eccentrics. They have slots 93 and bolts 94 to lock the eccentrics in their adjusted positions. The boxes 8 of the shaft 7 are similarly provided with adjusting means. In order that the supports of cylinders 2 and 6 may be lifted from place in the machine or lowered into position, I provide pairs of lifting-arms for each cylinder 2 and 6. The lifting-arms 96 for the cylinder 2 are provided with forks 97 at their upper ends to engage and support the shaft 3 and at their lower ends are provided with racks 98. The lifting-arms 99 for the cylinder 6 are similarly constructed and arranged. The shaft 19 is provided with the loose worms 100 and 101, adapted to be located thereon by means of the clutches 102 and 103, operated by the levers 104 and 105, respectively. These worms 100 and 101 engage worm-gears 106 and 107 on the shafts 108 and 109, respectively, which carry two gears 110 and two gears 111. The gears 110 mesh with the racks of the arms 96, and the gears 111 mesh with the racks of the arms 99. By these means the lifting-arms are hoisted and lowered to facilitate the lowering of the cylinders 2 and 6 to place or to facilitate the removal of these cylinders from place.

I will now describe the mechanism for operating the support or cylinder 11. 100

Fixed on the shaft 23 is a gear 112, meshing with the gear 113, fixed on the shaft 114, on which is mounted the loose gear 115, meshing with the gear 116, fixed to the cylinder 11. A clutch 117, operated by the rods 118, 105 which are actuated by the lever 119, serves to lock the loose wheel 115 on its shaft when the cylinder 11 is to be rotated.

I will now describe the mechanism whereby the cylinder 11 is moved to and from the cylinders 2 and 6 for the purpose of receiving an impression on its conveying-surface 12 from the primary surface 1 and carrying it over to the secondary surface 5. 110

The boxes 10, (see Figs. 11, 12, 13, and 14), 115 which support the shaft 9 of the cylinder 11, are capable of lateral movement in their recesses. Keyed on the ends of the shaft 9 and outside the frame are the eccentrics 120, working in the vertically-moving boxes 121. Fast on the shaft 9, near one end, is the gear-wheel 122, in mesh with which is the gear 123 on the shaft 124, turned by the hand-wheel 125. By turning the hand-wheel 125 the shaft 9 is rotated and with it the eccentrics 120, 120 which as they turn force the boxes 10 in a lateral direction. The eccentric-boxes 121 move slightly vertically in correspondence with the movement of the eccentrics. This mechanism is capable not only of moving the conveying-surface into contact with the primary and secondary surfaces, but also of applying to such contact all the pressure required. 130

I will now describe the details of the inking and dampening frames. (See Figs. 7, 8, 9, and 10.)

The inking-frame 17 is provided with the 5 bosses 126 to receive the shaft 16, which carries the main ink-distributing roller 45 and on which the frame is fixed, as already described. The rider-roller 53 is carried in boxes 127, supported in recesses 128. The 10 reciprocating rider 55 is also supported in recess 129. These recesses 128 and 129 are open at their outer sides and are closed by the arms 130, pivoted on the main part of the inking-frame by the bolts 131 and locked in 15 place by the nuts 132 on the bolts 133, which pass through apertures in the lower ends of these arms. When it is desired to take the rollers 53 and 55 out of the frame for the purpose of cleaning them or otherwise, the arms 20 130 are unfastened and swung back, and the rollers may then be removed. The boxes 127 are adjusted by the inner screws 134, having lock-nuts, and outer screws 135. The screws 135 pass through threaded apertures in the 25 arms 130, are provided with lock-nuts 136 and hand-wheels 137, and have heads 163, which rest in slots 164 in the inner sides of the boxes 127. Pivoted on the bolts 138 and preferably on the upper ends of the arms 130 are arms 30 139, having forks 140 at their lower ends engaging grooves 141 on the hand-wheels 137. The outer adjusting-screws 142 pass through threaded apertures in the arms 139 and loosely through apertures in the arms 130. These 35 screws have also lock-nuts 143. 144 are the inner adjusting-screws for the roller 55 and have lock-nuts, as shown. The rollers 53 and 55 are first set by their adjusting-screws; but when it becomes necessary to temporarily 40 separate these rollers from the form-inking rollers 56 and 57, as when the machine is stopped for an hour or so, the hand-wheels 137 are turned, and the rollers 53 and 55 thereupon separate from the inking-rollers 56 and 57. 45 These rollers 56 and 57 are supported in the recesses 147 and 148, respectively, open at their outer ends. These recesses are closed by the arms 149, pivoted by the bolts 150 on the main part of the frame 17 and locked in 50 place by the bolts 151 and nuts 152. The outer adjusting-screws 153 and 154 for these rollers pass through threaded apertures in the arms 149 and have lock-nuts, as shown. 155 and 156 are the inner adjusting-screws for 55 the rollers 56 and 57 and also have lock-nuts. When the rollers 56 and 57 are to be removed, as for the purpose of washing them or otherwise, the arms 149 are unlocked and swung back, when the rollers may be withdrawn. 60 157 is a lever pivoted on a bracket 158 and operating to reciprocate the roller 55. This lever has a lug 159 engaging an actuating-cam 160, rotating with the roller 45 on the shaft 16, (see Fig. 4,) and also has a lug 161 65 engaging a groove 162 in the roller 55. The inking-frame 13 and its rollers is a duplicate of the frame 17 and its rollers.

The dampening-frame 18 (see Figs. 9 and 10) is provided with bearings 165 to receive the shaft 16, on which, as already described, the frame is pivoted. The dampening-roller 59 is carried in boxes 166, which fit in recesses 167, in which they are adjustable by the inner screws 168, having lock-nuts, and by the outer screws 169, having lock-nuts and hand-wheels 170. The screws 169 have heads 171, which work in recesses on the inner sides of the boxes 166. The roller 59 has a gear 172, meshing with the idle gear 58, carried by the frame 18, whereby the dampening-rollers are 70 driven. The roller 59 may be withdrawn from its boxes by retracting the journal at one end, which may be slid into a recess in the roller by moving the pin 173 backward in its slot. The form-dampening rollers 60 and 61 are 75 carried in recesses 174 and 175, respectively, open on their outer sides, which are closed by the arms 176, pivoted to the frame 18 by bolts 177. Bolts 178, passing through apertures in the free ends of these arms, serve, 80 with their nuts 179, to lock the arms in place. These rollers are adjustable and held in place by the outer screws 180 and 181, respectively, having lock-nuts and passing through threaded apertures in the arms 176, and by the inner screws 182 and 183, having lock-nuts. When it is desired to remove the rollers 60 and 61, as for cleaning, the arms 176 are 85 swung back, when the rollers may be withdrawn from the frame. 90

I will now describe the specific construction of the support which carries the conveying-surface 12. This support is shown in the drawings as a cylinder 11 and provided with various accessories adopted for convenience. 95 It will be understood that this support or cylinder and its accessories may be variously modified and still carry out the main purpose of carrying over an imprint or impression from the primary surface to the secondary 100 surface. The cylinder is loosely mounted on the shaft 9, carried by the boxes 10, which are supported by the main frame between the primary and secondary surfaces, as already described. On the shaft 184 is carried a roll 105 of a suitable fabric, constituting the conveying-surface 12, and preferably transfer-paper. The shaft 184 is journaled in two extensible arms 185, provided with racks 186, telescoping with the arms 187 on the bosses 188, loose 110 on the shaft 9. A shaft 189, having gears 190 at both ends, which mesh with the racks 186, serves when rotated by its hand-wheel to move the arms 185, so as to carry the roll in and out of the recess 191, formed in the cylinder, the arms 185 being locked either in or out by the spring-latch 192. The bosses 188 have gear-teeth 193, meshing with the gears 194, fixed on the shaft 195, whereby the arms 185 and 187 may, when the roll is drawn out 115 of its recess 191, be moved around the periphery of the cylinder 11, so that the end of the paper may be caught by the grippers 196, carried by the rod 197 against an arm 214, on 120

115

120

125

130

which the springs 198 press. This rod carries on one end the cam 199. Fig. 18 shows the position of the arms constituting the roll-carrier just after the roll has been moved 5 out of the recess 191 and when it is ready to be moved back to the grippers. Fig. 19 shows the position of the carrier just after the grippers have been made to engage the paper, and Fig. 20 shows the position of the 10 carrier on its way back again to the recess 191 and as the carrier is spreading the paper over the periphery of the cylinder. Fig. 16 shows the position of the carrier when the paper 12 has been stretched in place and the carrier has been retracted into the recess. The roll-shaft 184 has a ratchet-wheel and ratchet 200 and 201, whereby the paper may be held tight on the roll and therefore taut over the cylinder. The paper generally rests 20 on a blanket 202, held in place by the cutter-bar 203 and the rod 204, which is provided with a ratchet-wheel and pawl 205 and 206. The cutter-bar 203 carries a knife 207, which extends between two rubber lips 208. 25 209 are two cams pivoted at 210 on the arms 185 and carrying the cutter-bar 211, having a recess to receive the knife when the two bars come together. The paper 12 extends between the two cutter-bars, (see Fig. 30 17,) and when they come together the paper is cut. The cams are actuated to move the bar 211 against the bar 203 by the cams 212, (see Fig. 3,) fixed on the shaft 7. One of the bosses 188 is provided with a bolt 213, which 35 engages the circular groove 214 on a hub of the cylinder 11, (see Fig. 15,) whereby the boss and its arm are removably held in place on the shaft. In the operation of the cylinder the paper 12 is first stretched over the 40 cylinder, as described, and the cylinder is then moved laterally by operating the hand-wheel 125, so as to bring the gears 50 and 116 into mesh and the end of the paper next the grippers in contact with the primary surface 45 1, which has been already fully prepared or developed, so as to bear the design which it is desired shall be made upon the secondary surface. The primary surface having been properly inked by the operation of its inking 50 and dampening rollers, actuated from the power-distributing shaft 23 and controlled by the clutch 24, as already described, and the inking and dampening frames having been swung out of the way by operating the hand-wheels 73 and 87, the primary surface is now 55 ready to print an impression upon the paper 12—*i. e.*, the conveying-surface. In bringing the gears 50 and 116 into mesh a marked tooth of one is always entered into a marked 60 recess of the other, so that the impression will be printed upon the conveying-surface always in identically the same place, this for the purpose of securing accurate register in the process of making the secondary printing-surface 65 and with reference to the subsequent printing. The cylinders 2 and 11, having the required pressure applied to the paper 12 and

secondary surface, are now rotated from the power-distributing shaft through the shaft 113 and the gear 115, controlled by the clutch 70 24, the clutch 24 having been previously reversed. Thus the primary surface prints its impression upon the paper 12 and by rolling contact. When the rotation of the cylinders 11 and 2 ceases, the cylinder 11 is brought into 75 the position shown in Fig. 21, having made a half-turn, and in this position, the starting end of the paper being opposite the cylinder 6, it is now moved over to the cylinder 6 by reversing the hand-wheel 25, and a marked 80 tooth and recess of the gears of these cylinders are intermeshed, so that the cylinders may always begin their coaction in precisely the same mutual relation. The cylinders 11 and 6, having the required pressure applied to 85 the paper 12 and secondary surface, are now rotated from the power-distributing shaft through the shaft 113 and gear 115, as before. As the cylinder 11 begins to rotate the gripper-cam 199 strikes the stud 215, projecting from the inner side of the main frame, and releases the paper 12 from the grippers, which adheres to the secondary surface and is turned over thereon. The progress of this 90 operation is shown at several stages in Figs. 95 21 to 24. Just before the latter end of the paper is reached in this operation the cutter-cams 209 are struck by the cams 212, and the cutter-bar 211 is driven against the cutter-bar 203, the lips 208 of which yield to the 100 pressure of the bar 211, thereby stretching the paper over the bar 211 as the knife 207 enters the recess therein and severs the paper. The cylinder 11 is now moved back to its initial position. The paper-transfer turned already over on the secondary surface is 105 damped and removed in the usual manner. The secondary surface is now developed and rolled up in the usual manner, the inking and 110 dampening rollers in the frames 17 and 18 being used in this operation, the two sets of rollers being operated and driven by the mechanism already described. The secondary surface has now become the secondary printing-surface and is ready to be employed for printing. Of course the secondary surface need 115 not necessarily be developed before removing it from the machine. It may be wholly or partly developed afterward. In removing the secondary surface from the machine the 120 clutch 103 is operated to lock the worm 101 on the shaft 19, which then by its rotation hoists the lifting-arms 99, thereby lifting the shaft 7, with its boxes, the locking-arms of 125 which have previously been thrown back. The entire cylinder 6, with its shaft and printing-surface 5, may then be removed by any 130 convenient means and mounted in a printing-press, or, if desired, the tubular printing-surface 5 may be slipped from its supporting cylinder 1, preferably onto a transporting apparatus, such as is described in my pending application filed July 12, 1898, Serial No. 685,764, and subsequently slipped onto a supporting-

cylinder of a printing-press adapted to receive it. I prefer to remove the printing-surface 5 from its cylinder 6, as last referred to. Both the primary and secondary surfaces and their cylinders are constructed with this end in view, the printing-surfaces having ribs adapted to slide in corresponding recesses on their cylinders, as shown in Figs. 3 and 29. The tubular or shell-like printing-surfaces are preferably made continuous and seamless and may consist of a suitable base, as copper, with an electrolytically-deposited zinc coating, or of a shell or tube cast, bent, or otherwise formed and may be made of zinc or other suitable material.

It will be evident from the above description that a printing-surface may be removed and another substituted for it in the same place, so that, if it is desired, the primary printing-surface may be removed after it has printed on the conveying-surface, and a secondary surface may be substituted for it in the same place and receive the impression or design on the conveying-surface by being brought into contact with it just as the primary surface was brought in contact with it and then rolled up and developed, or successive secondary surfaces may be substituted one for the other and so as to receive the same or different impressions or designs from the conveying-surface, according as the conveying-surface has successively printed upon it the same or different impressions or designs, or successive primary surfaces may be substituted one for the other, so as to print successively different designs or impressions upon the conveying-surface, which may convey each such design or impression to successive secondary surfaces. The intermeshing gears of the primary and secondary surfaces and the conveying-surface are not necessary in securing the rolling contact of one of these bodies with the other. Any one of these rolling bodies may be driven from the other by frictional contact, the intermeshing gears being dispensed with, as shown in Figs. 25, 26, and 27. Again, various forms of guiding means or pre-established guides may take the place of the marked teeth and recesses of these intermeshing gears and whether or not these gears are used. All that is necessary in this connection is that the coacting bodies, whatever their form may be, shall be brought into exact predetermined coöperating relation with reference to some sufficient guiding means or pre-established guides, whereby the design of the primary surface may be imposed upon the secondary surface in exact predetermined position.

In alluding to the positions of the printing-form and transfer-base on their respective supports and to their coöperating relation I use the terms "longitudinally" and "transversely" as referring to the two directions at right angles over said bodies, whether either or both of these bodies is flat or curved. If the body is curved, "longitudinal" would re-

fer to the axial direction and "transverse" to the circumferential direction.

What I claim as new, and desire to secure by Letters Patent, is—

1. The improvement in the art of making printing-surfaces which consists in imparting a design from a primary printing-surface to a secondary surface adapted to be developed into a printing-surface, the said primary printing-surface and the said secondary surface being arranged in a definite predetermined coöperating relation both longitudinally and transversely with reference to pre-established guides; whereby the design may be imposed upon the secondary surface in precise predetermined position and with reference to register; and developing said secondary surface into a secondary printing-surface of the character desired.

2. The improvement in the art of making duplicate printing-surfaces which consists in imparting a design from a primary printing-surface to a plurality of secondary surfaces adapted to be developed into printing-surfaces; said secondary surfaces being arranged in the same or equivalent definite predetermined coöperating relation with respect to the primary surface both longitudinally and transversely and with reference to pre-established guides; whereby the design may be imposed upon the secondary surface in precise predetermined position and with reference to register; and developing said secondary surfaces into secondary printing-surfaces of the character desired.

3. The improvement in the art of making duplicate and interchangeable printing-surfaces, which consists in imparting a design from a primary printing-surface to a plurality of secondary surfaces identical in working, size and shape, adapted to be developed into printing-surfaces; said secondary surfaces being arranged in the same or equivalent definite predetermined coöperating relation with respect to the primary surface both longitudinally and transversely and with reference to pre-established guides; whereby the design may be imposed upon the secondary surfaces in precise predetermined position and with reference to register; and developing said secondary surfaces into secondary printing-surfaces of the character desired.

4. The improvement in the art of making a series of registering printing-surfaces which consists in imparting from a series of primary printing-surfaces having registering designs, to a series of secondary surfaces adapted to be developed into printing-surfaces, and designed and constructed for register in printing, said secondary surfaces being arranged both longitudinally and transversely with reference to pre-established guides in the same or equivalent definite predetermined coöperating relation with respect to their respective coacting primary surfaces and with reference to the position and register of the secondary surfaces as secondary printing-surfaces;

whereby the designs may be imposed upon the secondary surfaces in precise predetermined position and with reference to register; and developing said secondary surfaces into secondary printing-surfaces of the character desired.

5. The improvement in the art of making a plurality of series of registering printing-surfaces which consists in imparting from a series of primary printing-surfaces having registering designs, to a plurality of series of secondary surfaces adapted to be developed into printing-surfaces; the members of each series of secondary surfaces being the same in working, size and shape and thereby interchangeable and being designed and constructed for register in printing, each primary surface being arranged both longitudinally and transversely with reference to preëstablished guides in the same or equivalent definite predetermined coöperating relation with respect to a plurality of secondary surfaces coacting therewith; whereby the design may be imposed upon the secondary surfaces in precise predetermined position and with reference to register; and developing said secondary surfaces into secondary printing-surfaces of the character desired.

6. The improvement in the art of making curved or cylindrical printing-surfaces which consists in imparting a design from a primary printing-surface to a curved or cylindrical secondary surface adapted to be developed into a printing-surface, said secondary surface having its design imposed upon it by rolling contact, the said primary printing-surface and the said secondary surface being arranged in a definite predetermined coöperating relation both longitudinally and transversely with reference to preëstablished guides; whereby the design may be imposed upon the secondary surface in precise predetermined position and with reference to register; and developing said secondary surface into a secondary printing-surface of the character described.

7. The improvement in the art of making curved or cylindrical lithographic printing surfaces which consists in imparting a design from a primary printing-surface to a curved or cylindrical lithographic secondary surface adapted to be developed into a printing-surface, said secondary surface having its design imposed upon it by rolling contact, the said primary printing-surface and the said secondary surface being arranged in a definite predetermined coöperating relation both longitudinally and transversely with reference to preëstablished guides; whereby the design may be imposed upon the secondary surface in precise predetermined position and with reference to register; and etching said secondary surface for the purpose of developing it into a secondary printing-surface of the character desired.

8. The improvement in the art of making continuous cylindrical lithographic-printing

surfaces which consists in imparting a design from a primary printing-surface to a continuous cylindrical lithographic secondary surface adapted to be developed into a printing-surface, said secondary surface having its design imposed upon it by rolling contact, the said primary printing-surface and the said secondary surface being arranged in a definite predetermined coöperating relation both longitudinally and transversely with reference to preëstablished guides; whereby the design may be imposed upon the secondary surface in precise predetermined position and with reference to register; and etching said secondary surface for the purpose of developing it into a secondary printing-surface of the character desired.

9. The improvement in the art of making printing-surfaces which consists in preparing a secondary surface of accurate predetermined size and shape to fit in a preëstablished seat in a printing-press, mounting said secondary surface in exact predetermined position both longitudinally and transversely with reference to preëstablished guides on a suitable support from which the secondary surface is removable; imparting from a primary printing-surface to said secondary surface mounted in position on its support, said primary and secondary surfaces being arranged in definite coöperating relation both longitudinally and transversely with reference to preëstablished guides, whereby the design may be imposed upon the secondary surface in precise predetermined position and with reference to register; and developing said secondary surface into a secondary printing-surface of the character desired.

10. The improvement in the art of making printing-surfaces which consists in preparing a curved shell-like secondary surface of accurate predetermined size and shape to fit in a preëstablished seat in a printing-press, mounting said secondary surface in exact predetermined position both longitudinally and transversely with reference to preëstablished guides on a suitable rotary support from which the secondary surface is removable; imparting from a primary printing-surface to said secondary surface mounted in position on its support, said secondary surface having its design imposed upon it by rolling contact, said primary and secondary surfaces being arranged in definite predetermined coöperating relation both longitudinally and transversely with reference to preëstablished guides whereby the design is imposed upon the secondary surface in exact predetermined position and with reference to register; and developing said secondary surface into a secondary printing-surface of the character desired.

11. The improvement in the art of making printing-surfaces which consists in preparing a continuous cylindrical lithographic secondary surface of accurate predetermined size and shape to fit in a preëstablished seat in a

- printing-press, mounting said secondary surface in exact predetermined position both longitudinally and transversely with reference to preëstablished guides on a suitable support 5 from which the secondary surface is removable; imparting from a primary printing-surface to said secondary surface mounted in position on its support, said secondary surface having its design imposed upon it by rolling 10 contact, said primary and secondary surfaces being arranged in definite predetermined co-operating relation both longitudinally and transversely with reference to preëstablished guides, whereby the design may be imposed 15 upon the secondary surface in precise predetermined position and with reference to register; and etching said secondary surface for the purpose of developing it into a secondary printing-surface of the character desired. 20 12. The improvement in the art of making curved shell-like lithographic-printing surfaces which consists in preparing a curved shell-like lithographic secondary surface and a rotary support therefor, said secondary surface and rotary support being made of a permanent size and shape to adapt them to fit 25 removably and replaceably one upon the other in an exact predetermined position both longitudinally and transversely, so that the secondary surface is adapted to 30 fit accurately in a preëstablished seat in a printing-press and so that the support is adapted to fit in a preëstablished seat in a transfer-press; preparing a primary printing-surface having its design located thereon in 35 an accurate predetermined position both longitudinally and transversely; mounting said primary surface and said secondary surface seated on its support in preëstablished seats in a transfer-press; imparting from the primary 40 surface to the secondary surface, said surfaces working in precise predetermined co-operating relation both longitudinally and transversely with reference to preëstablished guides; whereby the design may be imposed 45 upon the secondary surface in precise predetermined position and with reference to register; and developing said secondary surface into a printing-surface of the character desired. 50 13. The improvement in the art of making a plurality of curved shell-like printing-surfaces which consists in preparing a plurality of curved shell-like secondary surfaces and a rotary support therefor, said secondary surfaces and rotary support being made of a permanent size and shape to adapt the secondary surfaces to fit removably and replaceably on the support in the same exact predetermined position both longitudinally and 55 transversely so that the secondary surfaces are adapted to accurately fit in preëstablished seats in a printing-press and so that the support is adapted to fit in a preëstablished seat in a transfer-press; preparing one or more primary surfaces having its design located thereon in an accurate predetermined position both longitudinally and transversely; 60 mounting said secondary surfaces, each seated in turn on said support, successively in a transfer-press with a primary surface seated in said transfer-press; imparting from the primary surface or surfaces successively to the secondary surfaces, said primary and secondary surfaces being arranged in a precise predetermined coöperating relation both longitudinally and transversely with reference to preëstablished guides; whereby the design may be imposed upon the secondary surface in precise predetermined position and with reference to register; and developing said secondary surfaces into printing-surfaces of the character desired. 65 14. The improvement in the art of making curved shell-like lithographic-printing surfaces which consists in preparing a curved shell-like lithographic secondary surface and a rotary support therefor, said secondary surface and rotary support being made of a permanent size and shape to adapt them to fit removably and replaceably one upon the other in an exact predetermined position both longitudinally and transversely, so that the secondary surface is adapted to fit accurately in a preëstablished seat in a printing-press and so that the support is adapted to fit in a preëstablished seat in a transfer-press; preparing a primary printing-surface having its design located thereon in an accurate predetermined position both longitudinally and transversely; mounting said primary surface and said secondary surface seated on its support in preëstablished seats in a transfer-press; imparting from the primary surface to the secondary surface, said surfaces working in precise predetermined coöperating relation both longitudinally and transversely with reference to preëstablished guides; whereby the design may be imposed upon the secondary surface in precise predetermined position and with reference to register; and developing said secondary surface into a printing-surface of the character desired. 70 15. The improvement in the art of making printing-surfaces which consists in printing from a primary surface upon a suitable conveying-surface, imparting the design so printed from said conveying-surface to a suitable secondary surface adapted to be developed into a secondary printing-surface, the said primary surface, the conveying-surface, and the secondary surface, being arranged both longitudinally and transversely with reference to preëstablished guides in a definite and predetermined relation one to another, whereby, through the intermediation of the conveying-surface, the design is carried over from the primary surface and imparted to the secondary surface in an accurate and predetermined position; and developing the said secondary surface in suitable manner into a printing-surface of the character desired. 75 16. The improvement in the art of making curved printing-surfaces which consists in printing from a primary surface upon a suit- 80 85 90 95 100 105 110 115 120 125 130 135

able conveying-surface; imparting by rolling contact the design so printed from said conveying-surface to a suitable curved secondary surface adapted to be developed into a 5 secondary printing-surface, the said primary surface and the said secondary surface being arranged in a definite and predetermined co-operating relation with respect to the conveying-surface both longitudinally and trans- 10 versely and with reference to the pre-established guides, whereby, through the intermedia- 15 tion of the conveying-surface, the design is carried over from the primary surface and imparted to the secondary surface in an accurate and predetermined position; and de- 20 veloping the said secondary surface in a suitable manner, into a printing-surface of the character desired.

17. The improvement in the art of making 20 independent and interchangeable printing- surfaces, which consists in printing from a primary surface upon a suitable conveying- surface or series of successive conveying-sur- 25 faces; imparting the design successively from said conveying-surface or conveying-surfaces to a plurality of identical and interchangeable secondary surfaces, said secondary surfaces being successively arranged both longitudinally and transversely and with refer- 30 ence to pre-established guides in the same or equivalent definite and predetermined co-oper- 35 ating relation with respect to the conveying-surface, whereby through the intermedia- 40 tion of the conveying-surface or successive conveying-surfaces the design of the primary surface is carried over and imparted to the secondary surfaces in the same accurate and predetermined position; and developing said secondary surfaces in suitable manner, where- 45 by a series of printing-surfaces may be made having identical designs identically placed thereon.

18. The improvement in the art of making 45 a series of registering printing-surfaces adapt- 50 ed to co-operate in printing which consists in printing from a series of registering primary surfaces, upon a conveying-surface or a series of successive conveying-surfaces; imparting the designs from said conveying-surface or 55 conveying-surfaces to a series of secondary surfaces designed and constructed for register in printing, each secondary surface and its corresponding primary surface being ar- 60 ranged both longitudinally and transversely and with reference to pre-established guides in a definite and predetermined co-operating relation with respect to their conveying-surface and with reference to the position and register of said secondary surface as a print- 65 ing-surface, whereby, through the intermedia- 70 tion of the conveying-surface or conveying- surfaces, the designs of said series of register- 75 ing primary surfaces are carried over from the primary surfaces and imparted to the said secondary surfaces in accurate and predetermined positions and with reference to the register and co-operation of said secondary sur-

faces as printing-surfaces; and developing said secondary surfaces in suitable manner into printing-surfaces.

19. The improvement in the art of making a plurality of series of registering printing- surfaces, each series adapted to co-operate in printing, and the members of each series being identical and interchangeable with the corresponding members of the other series, which consists in successively printing from each member of a series of registering primary surfaces upon a suitable conveying-surface or a series of successive conveying-surfaces; im- 80 parting the designs of each primary surface successively from its conveying-surface or conveying-surfaces to a plurality of identical and interchangeable secondary surfaces, each of which is constructed and designed for reg- 85 ister in printing, the plurality of corresponding secondary surfaces of the several series being arranged both longitudinally and trans- 90 versely and with reference to pre-established guides in the same or equivalent definite and predetermined co-operating relation with re- 95 spect to their corresponding conveying-surface or conveying-surfaces and with reference to the position and register of said secondary surfaces as co-operating printing-surfaces, 100 whereby, through the intermedia- 105 tion of the conveying-surface or conveying-surfaces, the designs of the series of primary surfaces are carried over from said surfaces and imparted to a plurality of series of secondary surfaces in accurate and predetermined positions with reference to the positions and register desired in the ultimate use of each series of such sec- 110 ondary surfaces as co-operating printing-surfaces; and developing said secondary surfaces in suitable manner into printing-surfaces, 115 whereby from a series of registering primary surfaces a plurality of series of registering secondary printing-surfaces may be made, the members of each series of secondary printing- 120 surfaces being identical and interchangeable with the corresponding members of the other series of such secondary printing-surfaces.

20. The improvement in the art of making a plurality of series of continuous cylindrical tubular registering printing-surfaces, each series adapted to co-operate in printing and the members of each series being identical and interchangeable with the corresponding members of the other series, which consists in successively printing from each member of a series of registering primary surfaces upon a suitable conveying-surface or a series of successive conveying-surfaces; imparting the design of each primary surface successively from its conveying-surface or conveying-surfaces to a plurality of continuous cylindrical tubular identical and interchangeable sec- 125 ondary surfaces, each of which is constructed and designed for register in printing, each primary surface and its corresponding conveying-surface and secondary surface being ar- 130 ranged both longitudinally and transversely and with reference to pre-established guides

in the same or equivalent definite and predetermined coöperating relation as every other primary surface and its corresponding conveying - surface and secondary surface 5 and with reference to the position and register of said secondary surfaces as coöperating printing-surfaces, whereby through the intermediation of the conveying - surface or conveying-surfaces, the designs of the series 10 of primary surfaces are carried over from said surfaces and imparted to a plurality of series of secondary surfaces in accurate and predetermined positions with reference to the positions and register desired in the ultimate 15 use of each series of such secondary surfaces as coöperating printing-surfaces; and developing said secondary surfaces in suitable manner, into printing - surfaces, whereby from a series of registering primary surfaces 20 a plurality of series of registering secondary printing-surfaces may be made, the members of each series of secondary printing-surfaces being identical and interchangeable with the corresponding members of the other series of 25 such secondary printing-surfaces.

21. The improvement in the art of making printing-surfaces which consists in printing from a primary surface upon a suitable conveying-surface or series of successive conveying-surfaces; turning over and thus imparting the design so printed from said conveying-surface or conveying-surfaces to one or more suitable secondary surfaces adapted to be developed into a secondary printing surface or surfaces, the said primary surface, the conveying - surface, and the secondary surface, being arranged both longitudinally and transversely and with reference to preëstablished guides in a definite and predetermined relation one to another, whereby, through the intermediation of the conveying-surface, the design is carried over from the primary surface and imparted to the secondary surface in an accurate and predetermined 40 position; and developing the said secondary surface or surfaces in suitable manner into a printing surface or surfaces of the character desired, whereby a plurality of printing-surfaces suitable for printing the 45 same design, may be obtained.

22. The improvement in the art of making continuous cylindrical printing-surfaces which consists in printing from a primary surface upon a suitable conveying-surface, turning over and thus imparting the designs so printed from said conveying-surface to a suitable continuous cylindrical secondary surface adapted to be developed into a secondary printing-surface, the said primary surface 55 and the said secondary surface being arranged both longitudinally and transversely and with reference to preëstablished guides in a definite and predetermined coöperating relation with respect to their coacting conveying-surface, whereby, through the intermediation of the conveying-surface, the design is carried over from the primary surface 60

and imparted to the secondary surface in an accurate and predetermined position; and developing the said secondary surface in suitable manner, into a printing-surface of the character desired. 70

23. The improvement in the art of making identical and interchangeable printing-surfaces, which consists in printing from a primary surface upon a suitable conveying-surface or series of successive conveying-surfaces; turning over and thus imparting the design successively from said conveying-surface or conveying-surfaces to a plurality of identical and interchangeable secondary surfaces, said secondary surfaces being successively arranged both longitudinally and transversely and with reference to preëstablished guides in the same or equivalent definite and predetermined coöperating relation with respect to the primary surface, whereby through the intermediation of the conveying-surface or successive conveying-surfaces the design of the primary surface is carried over and 80 imparted to the secondary surfaces in the same accurate and predetermined position; and developing said secondary surfaces in suitable manner, whereby a series of identical and interchangeable printing-surfaces 90 may be made having identical designs identically placed thereon. 95

24. The improvement in the art of making a series of continuous cylindrical registering printing - surfaces adapted to coöperate in printing which consists in printing from a series of registering primary surfaces upon a series of successive conveying-surfaces; turning over and thus imparting the designs from said conveying-surfaces to a series of secondary surfaces designed and constructed for register in printing, each secondary surface and its corresponding primary surface being arranged both longitudinally and transversely and with reference to preëstablished guides 100 in a definite and predetermined coöperating relation with respect to their conveying-surface and with reference to the position and register of said secondary surface as printing-surface whereby, through the intermediation of the conveying-surfaces, the designs of said series of registering primary surfaces are carried over from the primary surfaces and imparted to the said secondary surfaces in accurate and predetermined positions and 105 with reference to the register and coöperation of said secondary surfaces as printing-surfaces; and developing said secondary surfaces in suitable manner. 110

25. The improvement in the art of making a plurality of series of registering printing-surfaces, each series adapted to coöperate in printing, and the members of each series being identical and interchangeable with the corresponding members of the other series, 115 which consists in successively printing from each member of a series of registering primary surfaces upon a suitable series of successive conveying-surfaces; turning over and 120

thus imparting the designs of each primary surface successively from its conveying-surfaces to a plurality of identical and interchangeable secondary surfaces, each of which 5 is constructed and designed for register in printing, the plurality of corresponding secondary surfaces of the several series being arranged both longitudinally and transversely and with reference to pre-established guides 10 in the same or equivalent definite and predetermined co-operating relation with respect to their corresponding conveying-surfaces and with reference to the positions and register of said secondary surfaces as co-operating 15 printing-surfaces, whereby, through the intermediation of the conveying-surfaces, the designs of the series of primary surfaces are carried over from said surfaces and imparted to a plurality of series of secondary surfaces 20 in accurate and predetermined positions with reference to the positions and register desired in the ultimate use of each series of such secondary surfaces as co-operating printing-surfaces; and developing said secondary 25 surfaces in suitable manner into printing-surfaces, whereby from a series of registering primary surfaces a plurality of series of registering secondary printing-surfaces may be made, the members of each series of secondary 30 printing-surfaces being identical and interchangeable with the corresponding members of the other series of such secondary printing-surfaces.

26. The improvement in the art of making 35 lithographic-printing surfaces which consists in printing from a primary surface upon a suitable conveying-surface, imparting the design so printed from said conveying-surface to a suitable lithographic secondary surface 40 adapted to be developed into a secondary printing-surface, the said primary surface, the conveying-surface, and the secondary surface, being arranged both longitudinally and transversely with reference to pre-established 45 guides in a definite and predetermined relation one to another, whereby, through the intermediation of the conveying-surface, the design is carried over from the primary surface and imparted to the secondary surface 50 in an accurate and predetermined position; etching said secondary surface for the purpose of developing it into a secondary printing-surface.

27. The improvement in the art of making 55 curved lithographic-printing surfaces which consists in printing from a primary surface upon a suitable conveying-surface; imparting by rolling contact the design so printed from said conveying-surface to a suitable 60 curved lithographic secondary surface adapted to be developed into a secondary printing-surface, the said primary surface and the said secondary surface being arranged in a definite and predetermined co-operating relation 65 with respect to the conveying-surface, the design being carried over from the primary surface and imparted to the secondary surface

in an accurate and predetermined position; etching said secondary surface for the purpose of developing it into a secondary printing-surface.

28. The improvement in the art of making a series of curved shell-like lithographic registering printing-surfaces adapted to co-operate in printing which consists in printing from 75 a series of registering primary surfaces, that is, imparting ink from said surfaces, upon a conveying-surface or a series of successive conveying-surfaces; imparting the designs from said conveying-surface or conveying-surfaces to a series of curved shell-like lithographic secondary surfaces designed and constructed for register in printing, each secondary surface and its corresponding primary surface being arranged in a definite and predetermined co-operating relation with respect to their conveying-surface and with reference to the position and register of said secondary surface as a printing-surface, the designs of 85 said series of registering primary surfaces being carried over from the primary surfaces and imparted to the said secondary surfaces in accurate and predetermined positions and with reference to the register and co-operation of said secondary surfaces as printing-surfaces; and developing said secondary surfaces 90 in suitable manner into printing-surfaces.

29. The improvement in the art of making curved rotary printing-surfaces which consists in printing from a primary surface upon 100 a suitable conveying-surface, imparting the design so printed from said conveying-surface to a suitable curved rotary secondary surface adapted to be developed into a secondary printing-surface, the said primary 105 surface, the conveying-surface, and the secondary surface, being arranged, both longitudinally and transversely with reference to pre-established guides, in a definite and predetermined relation one to another, whereby, 110 through the intermediation of the conveying-surface, the design is carried over from the primary surface and imparted to the secondary surface in an accurate and predetermined position; and developing the said secondary 115 surface in suitable manner into a printing-surface of the character desired.

30. The improvement in the art of making curved shell-like printing-surfaces which consists in printing from a primary surface upon 120 a suitable conveying-surface, imparting the design so printed from said conveying-surface to a suitable curved shell-like secondary surface adapted to be developed into a secondary printing-surface, the said primary surface, the conveying-surface, and the secondary 125 surface, being arranged, both longitudinally and transversely with reference to pre-established guides, in a definite and predetermined relation one to another, whereby, through the 130 intermediation of the conveying-surface, the design is carried over from the primary surface and imparted to the secondary surface in an accurate and predetermined position;

and developing the said secondary surface in suitable manner into a printing-surface of the character desired.

31. The improvement in the art of making curved shell-like lithographic-printing surfaces which consists in printing from a primary surface upon a suitable conveying-surface, imparting the design so printed from said conveying-surface by rolling contact to

10 a suitable curved shell-like lithographic secondary surface adapted to be developed into a secondary printing-surface, the said primary surface, the conveying-surface, and the secondary surface, being arranged, both longitudinally and transversely, with reference to preëstablished guides in a definite and predetermined relation one to another, whereby, through the intermediation of the conveying-surface, the design is carried over from the

15 primary surface and imparted to the secondary surface in an accurate and predetermined position; and developing the said secondary surface in suitable manner into a printing-surface.

20 32. The improvement in the art of making printing-surfaces which consists in preparing a removable and replaceable secondary surface and a support therefor, each of predetermined size and shape to adapt the one to fit

25 removably and replaceably upon the other in an exact predetermined position both longitudinally and transversely and with reference to preëstablished guides, and so that said secondary surface is adapted to fit in a preëstablished seat in a printing-press; printing from a primary printing-surface upon a conveying-surface, said primary and conveying surfaces being arranged in accurate predetermined co-operating relation both longitudinally and

30 transversely and with reference to preëstablished guides and thereby imposing the design of the primary surface in accurate predetermined position upon the conveying-surface; arranging said conveying-surface and said

35 secondary surface mounted on its support in accurate predetermined co-operating relation both longitudinally and transversely with reference to preëstablished guides, and imposing the design of the conveying-surface upon the

40 secondary surface in accurate predetermined position; and developing the secondary surface into a secondary printing-surface whereby said secondary surface may be mounted in its preëstablished seat in a printing-press

45 and made to print impressions in precise predetermined positions and with reference to register.

33. The improvement in the art of making printing-surfaces which consists in preparing a removable and replaceable secondary curved shell-like surface and a support therefor, each of predetermined size and shape to adapt the one to fit removably and replaceably upon the other in an exact predetermined

50 position both longitudinally and transversely and with reference to preëstablished guides, and so that the said secondary surface is

adapted to fit in a preëstablished seat in a printing-press; printing from a primary printing-surface upon a conveying-surface, said 70 primary and conveying surfaces being arranged in accurate predetermined co-operating relation both longitudinally and transversely and with reference to preëstablished guides, and thereby imposing the design of 75 the primary surface in accurate predetermined position upon the conveying-surface; arranging said conveying-surface and said secondary surface mounted on its support in accurate predetermined co-operating relation, 80 both longitudinally and transversely, with reference to preëstablished guides, and imposing the design of the conveying-surface upon the secondary surface in accurate predetermined position; and developing the secondary surface into a secondary printing-surface, 85 whereby said secondary surface may be mounted in its preëstablished seat in a printing-press and made to print impressions in precise predetermined position and with reference to register.

34. The improvement in the art of making printing-surfaces which consists in preparing a removable and replaceable secondary curved shell-like lithographic surface and a 90 support therefor, each of predetermined size and shape to adapt the one to fit removably and replaceably upon the other in an exact predetermined position both longitudinally and transversely and with reference to preëstablished guides, and so that said secondary surface is adapted to fit in a preëstablished seat in a printing-press; printing from a primary printing-surface upon a conveying-surface, 95 said primary and conveying surfaces being arranged in accurate predetermined co-operating relation both longitudinally and

100 transversely and with reference to preëstablished guides and thereby imposing the design of the primary surface in accurate predetermined position upon the conveying-surface; arranging said conveying-surface and said

105 secondary surface mounted on its support in accurate predetermined co-operating relation both longitudinally and transversely with reference to preëstablished guides and thereby imposing the design of the primary surface in accurate predetermined position upon the conveying-surface; arranging said conveying-surface and said

110 secondary surface mounted on its support in accurate predetermined co-operating relation both longitudinally and transversely with reference to preëstablished guides, and imposing the design of the conveying-surface upon the secondary surface in accurate predetermined position; and developing the secondary surface into a secondary printing-surface, 115

120 whereby said secondary surface may be mounted in its preëstablished seat in a printing-press and made to print impressions in precise predetermined positions and with reference to register.

35. The improvement in the art of making duplicate printing-surfaces which consists in preparing a removable and replaceable secondary surface and a support therefor, each of predetermined size and shape to adapt the 125 one to fit removably and replaceably upon the other in an exact predetermined position both longitudinally and transversely and with reference to preëstablished guides, and so that

130

said secondary surface is adapted to fit in a preëstablished seat in a printing-press, preparing a primary printing-surface identical in working size and shape with said secondary 5 surface and identical therewith in its adaptability to fit removably and replaceably in a preëstablished seat in a printing-press; printing from the primary printing-surface upon a conveying-surface, said primary and conveying surfaces being arranged in accurate 10 predetermined coöperating relation both longitudinally and transversely and with reference to preëstablished guides and thereby imposing the design of the primary surface in accurate 15 predetermined position upon the conveying-surface; arranging said conveying-surface and said secondary surface mounted on its support in accurate predetermined coöperating relation both longitudinally and 20 transversely with reference to preëstablished guides, and imposing the design of the conveying-surface upon the secondary surface in accurate predetermined position; and developing the secondary surface into a secondary 25 printing-surface whereby said primary and secondary surfaces may be mounted each in its preëstablished seat in a printing-press and made to print duplicate impressions in precise predetermined positions and with reference 30 to register.

36. The improvement in the art of making a series of registering printing-surfaces which consists in preparing a series of shell-like registering primary printing-surfaces, and a support 35 therefor, said primary surfaces being identical in working, size and shape and adapted to fit, removably and replaceably and successively, in the same accurate predetermined position, both longitudinally and trans- 40 versely, on their said support, and said support being constructed and designed to fit in a pre-established seat in a transfer-press; preparing a series of shell-like secondary surfaces and a support therefor, said secondary surfaces being identical in working, size and shape and 45 adapted to fit removably and replaceably and successively in the same accurate predetermined positions both longitudinally and trans- 50 versely on their said support, and said support being adapted to fit in a preëstablished seat in a transfer-press, and said secondary surfaces being constructed and designed to fit in preëstablished seats in a printing-press, printing from each primary surface successively mounted on its support seated in said transfer-press upon a conveying-surface, said 55 conveying-surface being seated in said transfer-press, each primary surface and its coöperating conveying-surface being arranged in accurate 60 predetermined coöperating relation both longitudinally and transversely with reference to preëstablished guides; printing the design of each primary surface from its conveying-surface upon a secondary surface 65 mounted on its support seated in said transfer-press, each secondary surface and its coöperating conveying-surface being arranged in ac-

curate predetermined coöperating relation both longitudinally and transversely with reference to preëstablished guides; and developing said secondary surfaces into secondary printing-surfaces of the character desired, whereby said secondary surfaces may be mounted at once in their preëstablished seats in the printing-press, and without the usual empiric adjustment be employed in printing 70 registering impressions. 75

37. The improvement in the art of making a series of curved registering printing-surfaces which consists in preparing a series of 80 curved shell-like registering primary printing-surfaces, and a rotary support therefor, said primary surfaces being identical in working, size and shape and adapted to fit, removably and replaceably and successively, 85 in the same accurate predetermined position, both longitudinally and transversely, on their said support, and said support being constructed and designed to fit in a preëstablished seat in a transfer-press; preparing 90 a series of curved shell-like secondary surfaces and a rotary support therefor, said secondary surfaces being identical in working size and shape and adapted to fit removably and replaceably and successively in the same 95 accurate predetermined position both longitudinally and transversely on their said support, and said support being adapted to fit in a preëstablished seat in a transfer-press, and said secondary surfaces being constructed 100 and designed to fit in preëstablished seats in a rotary printing-press; printing from each primary surface successively mounted on its support seated in said transfer-press, upon a conveying-surface, said conveying-surface being seated in said transfer-press, each primary surface and its coöperating conveying-surface being arranged in accurate predetermined coöperating relation, the same for all 105 the primary surfaces, both longitudinally and transversely with reference to preëstablished guides; printing by rolling contact the design of each primary surface from its conveying-surface upon a secondary surface 110 mounted on its support seated in said transfer-press, each secondary surface and its coöperating conveying-surface being arranged in accurate predetermined coöperating relation the same for all the secondary surfaces, both longitudinally and transversely with 115 reference to preëstablished guides; and developing said secondary surfaces into secondary printing-surfaces of the character desired, whereby said secondary surfaces may be mounted at once in their preëstablished seats in the printing-press, and, without the usual empiric adjustment, be employed in 120 printing registering impressions. 125

38. The improvement in the art of making a series of continuous tubular lithographic 130 registering printing-surfaces which consists in preparing a series of curved shell-like registering primary printing-surfaces, and a rotary support therefor, said primary surfaces

being identical in working size and shape and adapted to fit, removably and replaceably and successively, in the same accurate predetermined position, both longitudinally and transversely, on their said support, and said support being constructed and designed to fit in a preëstablished seat in a transfer-press; preparing a series of continuous tubular lithographic secondary surfaces and a rotary support therefor, said secondary surfaces being identical in working size and shape and adapted to fit removably and replaceably and successively in the same accurate predetermined position both longitudinally and transversely on their said support, and said support being adapted to fit in a preëstablished seat in a transfer-press, and said secondary surfaces being constructed and designed to fit in pre-established seats in a rotary printing-press, printing from each primary surface successively mounted on its support seated in said transfer-press, upon a conveying-surface, said conveying-surface being seated in said transfer-press, each primary surface and its coöperating conveying-surface being arranged in accurate predetermined coöperating relation the same for all the primary sur-

faces, both longitudinally and transversely with reference to preëstablished guides; printing by rolling contact the design of each primary surface from its conveying-surface upon a secondary surface mounted on its support seated in said transfer-press, each secondary surface and its coöperating conveying-surface being arranged in accurate predetermined coöperating relation, the same for all the secondary surfaces, both longitudinally and transversely with reference to preëstablished guides, and developing said secondary surfaces into secondary printing-surfaces of the character desired, whereby said secondary surfaces may be mounted at once in their preëstablished seats in the printing-press, and, without the usual empiric adjustment, be employed in printing registering impressions.

In testimony whereof I have signed my name to this specification in the presence of two subscribing witnesses.

EDWARD HETT.
